PORATION OF PENNSYLVANIA.

ELECTRICAL MEASURING INSTRUMENT.

1,226,056.

Specification of Letters Patent. Patented May 15, 1917.

Application filed November 28, 1913. Serial No. 803,447.

To all whom it may concern:

Be it known that we, WILLIAM M. BRADSHAW and WALTER G. MYLIUS, citizens of the United States, and residents of Wilkinsburg, in the county of Allegheny and State of Pennsylvania, have invented a new and useful Improvement in Electrical Measuring Instruments, of which the following is a specification.

10 Our invention relates to electrical measuring instruments, and it has for its objects to provide a highly effective and convenient friction compensating means therefor, and also a method of constructing said 15 means.

Various devices have been proposed to effect a compensation of the magnetic lines of force traversing the field structure of electrical measuring instruments for adjusting the same to operate correctly at light loads. We have provided, in our present invention, a device which may be stamped from a single piece of pliable conducting material and folded into such shape 25 as is suited for the purposes hereinafter set forth.

In the accompanying drawings, Figure 1 is a front elevation of the magnetizable structure of an electrical measuring instrument embodying our invention. Fig. 2 is a bottom plan view of the electrical measuring instrument shown in Fig. 1. Fig. 3 is a front elevation of a closed-circuit device embodying our invention. Fig. 4 is a top plan view of the device shown in Fig. 3, and Fig. 5 is a rear elevation of the device shown in Figs. 3 and 4.

Referring to the drawings, our invention is used in connection with a laminated 40 electromagnet or core member 1 having a central leg 2 that is joined, at one end, to two outer legs 3, and is separated therefrom, at its other end, by short curved air gaps 4, suitable rectangular winding spaces being provided between the middle, and around the outer legs. Each of the legs of the electromagnet is extended beyond the air gaps 4 to form poles that are disposed adjacent to a rotatable conducting 45 disk 5 constituting the armature or movable element of the meter. Adjustable means, which embody our invention, are provided for compensating for friction, the said means comprising two formed sheet

metal closed-circuit conductors 6 that are 55 pivotally mounted upon bolts 7 extending through cylindrical openings in the electromagnet core and assisting, as hereinafter explained, in securing the laminae together. The inner ends of the conductors 6 are 60 located and movable in the curved air gaps 4 between the central and outer legs of the electromagnet. The conducting members 6 are severally provided with a rectangular hole or opening 8 in the arm 8^a 65 of the same and a round hole or opening 9 in the oppositely disposed arm 9^a. The arm 8^a is provided also with a curved slot 10 so located as to receive a tightening screw 10^a, which is inserted through a block 11 70 attached to the laminae. The bolts 7 are severally provided with a head substantially rectangular in cross section and having a slot therein to receive a screw driver for turning the same, the head of the bolt 75 being of such a size and shape as to form a snug fit with the opening 8 in the arm 8^a of the conductor 6. The body of the bolt 7 is of such a size as to extend through a cylindrical opening provided therefor, in 80 the laminae, and it is screw threaded at its end to receive a nut 12 for fastening the laminae together and a second nut 13 for clamping one of the sides of the conductor 6 against the nut 12, while the rectangular 85 hole engages the head of the bolt at the other side to prevent bending and to insure parallel operation of the portion 14 in the air gap 4.

The conductors 6 are severally formed 90 by stamping sheets of metal into the desired shape, then clamping the portion 14 in a vise and twisting the two side pieces 8^a and 9^a through angles of 90° to form parallel operating arms.

95 Since the effect that the closed circuited conductors 6 have upon the relative speed of a meter is well known to those versed in the art, the following brief statements as to the operation will be sufficient for a clear 100 understanding of our invention: Since the magnetic lines of force traversing the member 1 travel in the directions indicated by the dotted lines in Fig. 1, if the conductors 6 are moved in a direction indicated by 105 the arrow, they will embrace a less number of such magnetic lines. The current, traversing the closed circuited conductors 6 by

reason of the well known fact that a closed circuited conductor will have a voltage induced in it, when embraced by varying magnetic lines of force, will set up magnetic lines of force around the same. The magnetic lines of force produced by the currents in the conductors 6 will oppose the magnetic lines of force traversing the electromagnetic member, and will cause the lines of force traversing the air gaps to be shifted in direction or the number of lines of force traversing one air gap to lag behind the number of lines of force traversing the other, thus increasing the speed of the rotating member at light loads to overcome the retardation of the same by reason of friction in its bearings.

Although the specific form of construction shown has been found highly effective and is that which is preferred, it is obvious that modifications thereof may be made within the spirit of the invention, and we desire to include all such modifications within the scope of the appended claims.

25 We claim as our invention:

1. In an electrical measuring instrument, the combination with a magnetizable core having a central member and side members spaced from each other at one end by air gaps, of two closed-circuit conductors comprising sides movable respectively in the said air gaps, sides having polygonal openings, and sides having circular openings, and bolts having polygonal heads for engaging said polygonal openings for adjusting the positions of the sides of the conductors in the said air gaps.

2. In an electrical measuring instrument, the combination with a magnetizable core having a central member and side members spaced from each other at one end by air gaps, of two closed-circuit conductors comprising sides movable respectively in the said air gaps, sides having polygonal openings, and sides having circular openings, bolts having polygonal heads for engaging said polygonal openings for adjusting the positions of the sides of the conductors in the said air gaps, and means for clamping both sides of the said closed-circuit conductors to the said bolts.

3. In an electrical measuring instrument, the combination with a laminated magnetizable core having a central member and side members spaced from each other at one end by air gaps, of two closed-circuit conductors comprising sides movable respectively in the said air gaps, sides having polygonal openings, and sides having circular openings,

circular openings, and means for engaging 60 said polygonal openings for adjusting the positions of the sides of the conductors in the said air gaps.

4. In an electrical measuring instrument, the combination with a laminated magnetizable core having a central member and side members spaced from each other at one end by air gaps, of two closed-circuit conductors comprising sides movable respectively in said air gaps, sides having 70 polygonal openings, and bolts having means for engaging said polygonal openings to adjust the positions of the sides of the conductors in the said air gaps.

5. In an electrical measuring instrument, 75 the combination with a laminated magnetizable core having a central member and side members spaced from each other at one end by air gaps, of two closed-circuit conductors comprising sides movable respectively in said air gaps, sides having 80 polygonal openings, and sides having circular openings, two bolts constituting means for pivotally mounting said closed circuit conductors, means for adjusting the relative positions of the sides of the conductors in the said air gaps, and means for securing the laminæ of said magnetizable core together.

6. In an electrical measuring instrument, 90 the combination with a laminated magnetizable member of a plurality of closed-circuit conductors severally comprising a side having a polygonal opening and a side having a circular opening, a bolt for engaging said openings, means associated with said bolt for securing the laminæ of said magnetizable member together, means for clamping both sides of said closed-circuit conductor to said bolt, and means for retaining said closed-circuit conductor in any given position.

7. A closed-circuit conductor constructed of sheet metal and comprising parallel sides, one of which has a circular opening 105 therein and the opposite one of which has a polygonal opening and a slot therein, the other sides being substantially in the same plane and at right angles to the sides having the openings therein.

In testimony whereof, we have hereunto subscribed our names this 18th day of Nov. 1913.

WILLIAM M. BRADSHAW.
WALTER G. MYLIUS.
